DRUM BUNG WRENCH

Ruben R. Motl, 3573 Armstrong St.,
San Diego, Calif. 92111

Filed June 27, 1966, Ser. No. 2,828

Term of patent 14 years

(Cl. D54—16)

FIGURE 1 is a perspective view, from one side, of a drum bung wrench, showing my new design;

FIGURE 2 is a top plan view thereof;

FIGURE 3 is a bottom plan view thereof;

FIGURE 4 is an end elevational view as taken from the left hand side of FIGURE 1; and

FIGURE 5 is an end elevational view as taken from the right hand side of FIGURE 1.

I claim:

The ornamental design for a drum bung wrench, as shown and described.
